UNITED STATES PATENT OFFICE.

WILLIAM POHLMAN, OF MIDDLETOWN, NEW YORK.

ADJUSTABLE BORING AND REAMING TOOL.

1,082,553.

Specification of Letters Patent.

Patented Dec. 30, 1913.

Application filed December 18, 1911. Serial No. 666,438.

To all whom it may concern:

Be it known that I, WILLIAM POHLMAN, a citizen of the United States, residing at Middletown, in the county of Orange and State of New York, have invented a new and useful Adjustable Boring and Reaming Tool, of which the following is a specification.

The present invention relates to improvements in adjustable boring and reaming tools, the primary object of the invention being the provision of a tool, the holder portion of which is provided with two sets of radially disposed cutters or tools, each set of which is provided with its individually controlled means whereby the projection or retraction of its respective set may be adjusted to an exactness, so that the tool may be set at once to the desired diameter and with micrometric accuracy, in a similar manner as a micrometer gage or caliper, except that the present construction provides one set of tools for cutting the rough portion of the diameter of a bore while the other set is the finishing set.

A further object of the present invention is the provision of an adjustable reaming and boring tool having two sets of adjustable cutters or tools, so disposed with relation to each other as to give the desired original or rough cut and simultaneously the finishing cut, the cutting edges of the respective tools being disposed at an angle to the longitudinal axis of the tool body and in such relation thereto as to render the sharpening thereof more easy and the adjustment, that is the projection or retraction of the respective tools or cutters, more exact and easy.

With the foregoing and other objects in view which will appear as the description proceeds the invention resides in the combination and arrangement of parts and in the details of construction hereinafter described and claimed, it being understood that changes in the precise embodiment of invention herein disclosed can be made within the scope of what is claimed without departing from the spirit of the invention.

In the drawings—Figure 1 is a view illustrating the complete adjustable boring and reaming tool, a portion thereof being shown in elevation while the other portion, approximately the one-half thereof, is shown in longitudinal section taken on a line, whereby a quadrant of the complete tool is

removed. Fig. 2 is a longitudinal sectional view taken on line 2—2 of Fig. 3. Fig. 3 is a cross section taken on line 3—3 of Fig. 1. Fig. 4 is a cross section taken on line 4—4 of Fig. 1. Fig. 5 is a sectional view showing one of the upper cutters in elevation and relative to the adjacent portion of the tool.

Referring to the drawings, the numeral 1 designates the main body of the shank of the boring or reaming tool, which is provided with the enlarged lower end or head 1', having the concentric socket or chamber 2 formed in the same and extending into the body of the shank.

Formed in the enlarged portion 1' of the tool carrying body are the two sets of slots or apertures 4 and 5 respectively, in which are slidably mounted for retraction and projection the respective cutters or tools 6 and 7. The cutters 6 are disposed so that the cutting ends thereof will assume an angle as clearly shown in Fig. 1, whereas the cutters 7 are disposed so as to assume an angle of substantially the same degree. The cutters 7 are what are termed the primary or first cutters to perform the reaming operation after the rough cut or bore is made, while the cutters 6 are the finishing cutters to produce the desired smooth bore. Although as shown, these cutters are disposed so that one may be used for the first cut and the other for the second cut, it is to be understood that one or the other sets may be used independently of the others.

In order to properly adjust the respective cutters 6 so as to retract or project the cutting edges thereof the desired distance, the portion of the shank above the enlargement 1 is screw threaded as at 1^a, and mounted for sliding movement within the upper end of the bore 2 thereof, is the concentrically disposed cutter adjusting wedge 8, which is provided with the diametrically disposed slot 9 through the upper end thereof, so as to receive the diametrically disposed bar 10 whose outer threaded ends 11 project through slotted portions 1^b of the shank of the tool to engage the threaded portion 12 of the adjusting sleeve or collar 13. This collar 13 is also fitted upon the threads 1^a, whereby the rotation of the sleeve 13 will impart a vertical or longitudinally sliding movement to the bar 10 and consequently the cylindrical wedge 8, the wedging portions 14 formed upon the lower portion of the said

wedge 8 being disposed to operably engage the inner ends 6' of the upper set of cutters 6, whereby the lowering of the said wedge 8 will cause the projection of the cutter 6 while the raising thereof will permit the retraction of the cutters 6. Simultaneously with the action of the wedge 8 upon the inner ends of the cutters 6, the inclined or wedging surfaces 15 and 16 of the respective sleeve 13 and the enlarged portion 1' of the tool holding shank will engage the inclined edges 6'' of the cutters 6 and act as a means to insure the locking of the respective cutters 6 in their desired adjusted position.

In order to adjust the respective lower cutters 7 so as to permit the cutting edges thereof to be retracted or projected to the desired degree, the lower portions of the said cutters 7 are provided with the inclined wedging walls 7' 7'' respectively, the walls 7' being normally held in engagement at all times with the inclined wall 5' of the respective slots 5 of the enlarged portion 1' of the head of the tool. The adjusting collar or sleeve 17 is fitted upon the lower threaded end of the main shank so as to be movable to cause the respective inclined walls 5' of the apertures 5 to ride upon the inclined walls 7' of the respective cutters 7, the movement upward thereon retracting the cutters while the movement downward with relation thereto permits the projection of the cutters.

In order to properly lock the cutters and also assist the sleeve 17 in the retraction and projection thereof, a threaded plug 19 carrying a washer 20 is mounted within the lower threaded end 18 of the bore 2 of the shank and carries the concentrically disposed feed screw 21 which is carried by the rotatable cap 22 mounted within the plug 19 and provided with means whereby the same may be rotated to cause the screw 21 to impart the desired movement to the wedging plug 23, which is somewhat similar to the plug 8 and is provided with the inclined upper wedge portion 24 engaging the inclined walls 7'' of the respective cutters 7 and thereby coacting with the inclined walls 5' of the adjusting sleeve 17, to permit the retraction and projection of the respective cutters and the locking thereof in the desired adjusted position.

Each of the respective wedging plugs 8 and 23 is provided with the respective slots 26 and 28 which coact with the respective pins or keys 27 and 29 to prevent a rotary movement of the respective plugs but permit a sliding movement thereof within the bore of the shank of the tool. In order that the retraction and projection of the respective cutters may be regulated to a nicety, so that the operator may adjust them and know exactly by a micrometer gage the distance of the projection or retraction, a graduated scale 13^a is formed

upon the lower rim or edge of the upper adjusting sleeve 13, and disposed for coaction with the indicator or pointer 24 carried upon the enlarged portion 1' of the tool body and disposed to project beyond the lower rim of the sleeve 13 above the graduations. The lower adjusting sleeve 17 is provided with like micrometer graduations 17^a while carried by the enlarged body portion 1' of the tool holder is the indicator or pointer 25 similar to the pointer 24 and is disposed to coact with the graduations upon the scale 17^a.

By providing the sleeve 13 and the locking sleeve 13', as clearly illustrated, it is evident that the threaded ends of the bar 10 are fully protected so that the fine adjustment afforded thereby will in no way be interfered with, the positioning of the sleeve being such that the tool may be adjusted to an exactness, both in retraction and projection without disturbing any of the interior arrangement of the tool.

From the foregoing description taken in connection with the drawings, it is evident that a boring or reaming tool constructed according to and embodying the present invention, may be readily and easily adjusted to project or retract the respective sets of cutting tools to the desired degree so that the said cutters or tools may be actuated and locked in the various desired positions, and further that by providing each set of tools as herein set forth, the first set entering the bore first will ream the rough cut thereof while the second set entering the same will produce a finish. It is also evident that either one of the said cutters may be used independently, the first set being projected beyond the second set when it is desired to use the first set only, or the second set may be projected beyond the first set.

In operation should it be desired to project the respective cutters 6, it is simply necessary to release the lock nut 13' and rotate the sleeve 13, so as to move the concentric wedge 8 downwardly, the inclined faces 14 thereof resting upon the inner ends 6' of the respective cutters 6 so as to project the cutting ends thereof, while simultaneously with this movement the sleeve 13 will be raised so that its wedging surface 15 will ride upon the inclined faces 16 of the respective cutters 6 and thus permit the projection of the cutters and yet at the same time form a coacting wedging means with the lower end of the wedging plug 8 to lock the cutters at the desired adjustment upon the stoppage of the movement of the sleeve 13. When the gage 13^a indicates that the cutters are projected the proper distance, the lock nut 13' is locked so as to hold the sleeve 13 immovable and the cutters 6 are now ready for use. To retract the cutters the lock

operation is simply reversed causing the retraction of the wedge 8 and the consequent projection of the lower end of the sleeve 13.

In order to actuate the cutters 7, the sleeve 17 is rotated, such rotation causing the same to either move or ride upon the inclined surface 7' of the respective cutters 7 to cause the retraction or projection thereof, while the disk 22 is rotated to move the wedging 10 plug 23 in an opposite direction to the movement of the sleeve 17, the wedging faces of the respective sleeve 17 and plug 23 engaging the wedging surface 7' and 7" of the cutters 7 so as to retract or project the same 15 and retain them in the desired adjustment according to the indication upon the micrometer gage 17a of the sleeve 17.

What is claimed is:

A tool of this character, including a shank having an enlarged lower end, the junction between the enlarged portion and the reduced portion being outwardly and downwardly inclined, the enlarged portion and a portion of the reduced portion of the shank being 20 tubular, the reduced portion having diametrically disposed elongated slots communicating with the bore thereof, the portion of the shank above the slots being exteriorly threaded, the shank at the junction of the 25 enlarged portion and in the enlarged portion being provided with a plurality of radial slots, a plurality of cutters disposed for radial sliding movement in the latter 30

slots, each cutter having an inclined edge to correspond with the inclined portion of 35 the shank, an adjusting and locking wedge mounted slidably in the upper end of the bore of the shank and having a diametrical slot through its body, said slot being of lesser length than the elongated slots of the 40 shank, a bar of greater length than the diameter of the wedge fitting in the slot thereof and having the outer faces of its ends threaded and disposed through the elongated slots of the shank for sliding movement therewithin, a sleeve having internal threads and an inclined rim disposed for rotation upon the shank adjacent the enlarged portion, the threads engaging the threaded ends of the bar, whereby the bar is 45 moved longitudinally of the shank to project and retract the wedge, the inclined rim coacting with the inclined portion of the shank and the cutters to project and retract the cutters and lock the same in adjusted 50 position, and a locking sleeve disposed upon the shank and in coactive relation to the upper end of the adjusting sleeve.

In testimony that I claim the foregoing as my own, I have hereto affixed my signature 55 in the presence of two witnesses.

WILLIAM POHLMAN.
